UNITED STATES PATENT OFFICE

168,925

MAILBOX

Howard A. Daum, Pittsburgh, Pa.

Application September 17, 1952, Serial No. 21,506

Term of patent 14 years

(Cl. D74—9)

To all whom it may concern:

Be it known that I, Howard A. Daum, a citizen of the United States, residing at Pittsburgh, county of Allegheny and State of Pennsylvania, have invented a new, original, and ornamental Design for a Mailbox, of which the following is a specification, reference being had to the accompanying drawing, forming a part hereof, in which:

Fig. 1 is a front view in perspective of a mailbox showing my new design; and

Fig. 2 is a rear view in perspective thereof.

I claim:

The ornamental design for a mailbox, as shown.

HOWARD A. DAUM.
